PHOTOGRAPHIC LAYOUT TABLE

Joseph F. Knapp, Naugatuck, Conn., assignor to Knapp Machine Corporation, Waterbury,
Conn., a corporation of Connecticut

Application January 20, 1948, Serial No. 143,891

Term of patent 14 years

(Cl. D61—1)

To all whom it may concern:

Be it known that I, Joseph F. Knapp, a citizen of the United States, residing in Naugatuck, county of New Haven, and State of Connecticut, have invented a new, original, and ornamental Design for a Photographic Layout Table, of which the following is a specification, reference being had to the accompanying drawing, forming part thereof.

The single figure on the drawing is a perspective view of the photographic layout table showing my new design.

I claim:

The ornamental design for a photographic layout table, substantially as shown.

JOSEPH F. KNAPP.
